ARMING DEVICE

Allen S. Clarke, Washington, D. C., assignor to the
United States of America as represented by the
Secretary of War

Application November 25, 1947, Serial No. 788,075

3 Claims. (Cl. 102—70.2)

(Granted under Title 35, U. S. Code (1952),
sec. 266)

1

The invention described herein may be manufactured and used by or for the Government for governmental purposes without the payment of any royalty thereon.

My invention relates to fuses of the general kind referred to in my co-pending application Serial No. 788,074, filed November 25, 1947, and has for an object to present a novel construction of means for locking the generator rotor in an electric fuze in such manner that it will continue to operate effectively only under actual flight conditions due to firing of a projectile equipped with the fuze, as in launchers or guns.

It is a special purpose of this invention to present a construction which can be produced at low cost in a form to be operated by a mechanical arming device which may also include electrical arming means in accordance with my said other application.

It is also a purpose of this invention to permit the incorporation of the specific latch or lock for the generator by the use principally of the timing and arming train of my said co-pending application, or other.

Additional objects, advantages and features of invention reside in the construction, arrangement and combination of parts involved in the embodiment of the invention, as will appear or be understood from the following description and accompanying drawings, wherein:

Fig. 1 is an isometric perspective of the operating parts of my invention without framing or detonating means for the primer carried in the arming rotor, these being discretionary and adaptable from the disclosure of my said co-pending application, as well as by the use of other means known in the art.

Fig. 2 is a similar view showing the unlocked condition.

Fig. 3 is a fragmentary longitudinal section of the lower part of the fuze.

Referring specifically to the drawing, there is illustrated conventionally the rotor 25 of a generator mounted on a shaft 26, which may be coaxial with a fuze assembly and shell, and may be included in a framed and cased unit substantially of the form and size shown in my said co-pending application. A reduction gear train and arming rotor (shown) are also adapted to be mounted in the framing of said application, and an arming rotor here may be located substantially as accommodated in the said application.

For these reasons the details of shell, fuze framing and casing are not illustrated in Fig. 1

5

and only in part in Fig. 3 since the support of the operative parts in their relative locations and cooperative relations involve moderate mechanical skill. Similarly the specific detonating circuits are not illustrated.

The shaft 26 is utilized as in the said other application with a lower worm portion 36 to drive a gear train including counter-shaft 37, to drive large gear 38, which in this instance is mounted directly on the arming rotor 40. The latter is revoluble on trunnions 39 the upper of which is carried in a bearing on the plate 19. The arming rotor is accommodated in a chamber 41 formed by a tubular wall 44 inserted within the mounting tube 42 carrying the capacitor 39, at its outer end. The wall is pinned at 45 to the plate 19, and the tube 42 has the ring 43 held by the in-flanged lower end of the case 16 which encloses the entire generator and arming unit. The lower trunnion of the arming rotor is set in the interrupter plate 46, pinned at 47 to the wall 44, and the interrupter has the usual flash port 48 therethrough, while the rotor 40 has the detonator hole 53 therethrough located initially opposite the port 48 as indicated in Fig. 3. A detonator 59 is conventionally fixed in the hole 53. The booster 50 is mounted below the interrupter plate, its case 51 being engaged in the ring 43 by screw threads, by which the booster case is caused to press the interrupter and wall 44 against the plate 19.

For the purpose of illustration, a framing plate 19 is located high enough in the framing to afford a space thereunder above the flange of the capacitor tube 42, which forms part of the chamber 41 within the wall 44, and outwardly of the latter accommodates a small gear 37', mounted on the lower end of the shaft 37 which is extended through a suitable bearing in the plate 19. The gear 37' is meshed with an interrupted gear 38 fixed or formed concentrically on the upper periphery of the arming rotor, the latter being suitably rabbeted at 38' where the gear is interrupted, the interruption being so located that in the driving of the rotor 40 by the gear 37', the latter will enter the interruption as the hole 53 becomes aligned with the port 48, which is the armed position of the rotor, the brushes 61 or other forms as determined on at this time closing the circuit from the detonator squib to the terminal studs 62 by which the detonation circuit from a proximity or other timed circuit closing device may be completed, and permitting such other circuits to be complete as may be provided for.

2

The reduction gear train includes a worm gear 9, driven by the worm 38, and a second worm 10 extended axially from the gear 9 driving an upper gear 11 on the shaft 37 by which the latter is operated. The worm 10 is extended a distance past the gear 11 and has fixed thereon a planiform sector 12 which, as shown, includes an angle of approximately 270 degrees, although a smaller portion thereof may be of utility in the functioning of the device, as will appear. This leaves a gap 13, the use of which will be explained.

Pivoted on the framing there is a generator lock lever 70 swingable in a vertical plane radial to the shaft 26. This lever is formed of a broad planiform plate normally extending approximately horizontally from its pivot toward the shaft 26 and being notched at 71 on its end so as to receive the shaft therein. It is held yieldingly in its horizontal position by a contractile spring 72 conveniently anchored thereabove. Set permanently through the shaft 26 there is a cross pin 73, the ends of which rest upon the fingers 74 at the end of the lever and stop the upward movement of the lever. The extremities of the fingers 74, formed by the notching of the lever, are turned upward sharply, forming stop flanges 75 extending vertically close beside the pin 73, so that while the lever is held at this upper limit of its movement the shaft 26 is stopped by engagement of the pin against one of the flanges 75.

Pivoted on the plate 19 to swing in a vertical plane parallel to the worm 10, there is an upstanding keeper lever 76 movable at its upper end toward and from the lock lever 70, being urged toward the lock layer by a contractile spring 77 or other spring. It is provided with a keeper lug 78 at its upper end projected in the direction of the lock lever, and at such level as to engage over and hold the lock lever 70 at a lowered position with the flanges 75 clear of the pin 73, if the lever 76 is free to respond to the urging of the spring 77. The keeper lever is normally detained and held from this engaging movement by a rigid arm 79 formed integrally thereon, extended at right angles to the plane of movement of the keeper lever and toward and resting against the side of the sector 12. The arm 79 laps the sector less than the depth of the gap 13, however, so that when the worm 10 turns through the predetermined angle of its movement determined by the initial setting of the gearing, the arm 79 will be freed of obstruction by the sector 12 by passing through the gap 13, and the lever 76 will respond to the spring 77, moving into engagement with the lever 70 with the lug 78 interposed in the direction which the lock lever tends to move under urging of its spring 72.

With the construction described, the generator rotor is at all normal times held from rotation by the action of the spring 72 lifting the lever 70 so that one flange 75 engages the cross pin 73.

On firing of a projectile equipped with the fuze (the upper part of Figure 1 being the forward part), inertia of the lever 70 causes it to swing rearwardly against the action of the spring 72, clearing the pin 73. This permits the rotor to be driven by the wind vane with which the fuze is equipped (not shown), which may conform to well known practices in such devices. After a predetermined distance in flight, operation of the worm 10 brings the gap 13 into alignment with the arm 70, permitting the latter to pass through the sector 12, the keeper lever 76

thereby engaging and holding the lock lever in disengaged position permanently. Therefore, when deceleration of the projectile begins the lock lever cannot return to engagement with the pin 73.

Operation of the generator begins with release of the pin 73 and potential is supplied to the electrical controls, condensers, and the like, according as these may be constructed and connected. However, communication of detonating current to the detonator or completion of the explosive train to the primer or squib is not possible at once, because of the displaced position of the arming rotor with respect to the port 48. Movement of the arming rotor is begun, however, coincident with turning of the generator rotor and before the keeper lever 76 has operated. After the desired extent of flight by which sufficient rotation of the shaft 26 has been produced to move the arming rotor to armed position, the interruption in the gear 38 will have come into registry with the gear 37, so that driving of the arming rotor ceases. Thereafter, the action of the fuze is dependent on the function of such control devices as may be used in association with the generator output, not shown.

The invention has been disclosed in a form suited to operation in fuzes of the kind referred to, but it will be understood that this disclosure is purely exemplary, the form of the parts being subject to changes to fit them to approved current practices of the time of production, and the particular forms of framing and housing and circuit arrangement and closing are purely formal and not limiting.

It will be noted that if the fuze or projectile equipped therewith is dropped in such manner as to cause the lock lever to move away from the pin 73 when the dropped article strikes a floor or other object, there will not occur sufficient movement of the generator rotor to operate the sector 12 sufficiently to clear the arm 79, and the lock lever will be free to return to locking relation with the shaft 26 and pin 73. If the latter should have turned to a position angularly different from that illustrated in Fig. 1, one end of the pin will strike on the flat portion of the lever inwardly of the flanges 75, and it will be permitted no more than 178 degrees rotation thereafter before the pin 73 again engages the flanges 75.

I claim:

1. In a generator powered fuze having a generator rotor arranged to turn on a fore-and-aft axis of a projectile equipped therewith, a radial projection fixed with the rotor, a locking device rearwardly of the path of the radial projection, said locking device comprising a plate pivoted at one end transversely of said axis and having its opposite end formed with two parallel arms which are normally in releasable engagement with said projection, said arms movable generally in an arc longitudinally of said axis from lock position, to unlock position, a spring urging the locking device toward a locking position in said path, said spring being yieldable to the forces of inertia of the locking device under set-back on firing, a keeper movable into and spring urged toward position to hold said locking device out of said path and a delay device operatively connected with the rotor and said keeper constructed to normally hold the keeper free of the locking device, and movable to free the keeper at a given stage of movement of the delay device.

2. In a projectile and generator powered fuze

having a generator rotor rotatable on a fore-and-aft axis of the projectile, a rotating shaft connected with the rotor having a radial projection fixed thereon, a lock lever pivoted laterally of the shaft swingable to rest against the projection from the rear and having a stop thereon to engage in the path of the projection and hold the same from rotation and being movable to a rear unlock position free of the projection, a keeper lever pivoted to swing into holding position in the path of the lock lever when the latter is at said unlock position, a movable stop member normally in the path of the keeper from said normal position to said holding position, and operative connections between the stop member and shaft to move the same from said path of the keeper lever.

3. In a generator powered fuse having a generator rotor arranged to turn on a fore-and-aft axis of a projectile equipped therewith, a radial projection fixed with the rotor, a locking device rearwardly of the path of the projection, said locking device comprising a plate pivoted at one end transversely of said axis and having its opposite end formed with two parallel arms which are normally in releasable engagement with said projection, said arms movable generally in an arc longitudinally of said axis from lock position to unlock position, a spring urging the locking device toward a locking position in said path, said spring being yieldable to the forces of inertia of the locking device under setback on firing, a keeper movable into and spring urged toward position to hold

said locking device out of said path, a delay device operatively connected with the rotor and keeper constructed to normally hold the keeper free of the locking device and movable to free the keeper at a given stage of movement of the delay device, said delay device including a counter shaft spaced from and parallel to said axis, an arming rotor having an interrupted gear thereon, a gear on the counter shaft meshed therewith, an interrupter plate having a port formed therein under said arming rotor, a detonator carried by the arming rotor exposed to the plate and movable with the arming rotor to align with the port, the interruption of the gear being angularly disposed with relation to said detonator to align with said gear on the counter shaft when the detonator is aligned with the port.
